UNITED STATES PATENT OFFICE

KARL AUGUST LEHMANN AND ALEXANDER VARREN, OF ESSEN, GERMANY, ASSIGNEES
TO FRIED. KRUPP AKTIENGESELLSCHAFT, OF ESSEN-ON-THE-RUHR, GERMANY

ISSUING VOUCHERS IN CASH REGISTERS

Application filed July 31, 1928, Serial No. 296,436, and in Germany September 17, 1927.

The invention relates to a cash register equipped with a mechanism for issuing besides an original voucher one or more duplicates thereof, as is required with certain transactions, e. g. a carriage bill and some duplicates thereof. In transactions of this nature the value amount appearing on the vouchers has to be transmitted to the adding mechanism only once and the consecutive number of the original voucher must correspond to that appearing on the duplicates.

When the issue of the original voucher and the appurtenant duplicates is executed in one single operation of the machine, very complicated printing and paper feeding mechanisms are required, which considerably raise the costs of manufacture of the machine and reduce the reliability of its mode of operation.

In order to perform, in an ordinary cash register, the issue of these vouchers according to our invention without the mentioned printing and paper feeding mechanisms, this issue takes place in successive operations, the operation by which the original voucher is issued preparing the duplicate issuing operations, while a repeated setting of the values appearing on the original voucher and the duplicates and their addition is prevented in the duplicate issuing operations by mechanisms influenced during the operation that issues the original voucher.

Hence, as many cash operations are required in the present cash register, as vouchers are to be issued, whilst the setting of the value amount takes place only once, the feed of the consecutive number is thrown out during the duplicate issuing operation, and the set value amount is transmitted to the adding mechanism only once, namely during the operation that issues the original voucher.

In order that our invention may be more easily understood, a preferred embodiment of it is illustrated by way of example in the drawings which accompany and form part of this specification. In these drawings:

Figures 1 and 2 are lateral views of the mechanism serving to issue a duplicate voucher,

Figure 3 is a fragmentary side view of a

mechanism serving to issue a plurality of duplicates.

Fig. 4 is a side elevation of the setting device with an amount key-bank and the coupling device for the adding and printing mechanism,

Fig. 5 is a side elevation of the printing mechanism,

Fig. 6 is a front elevation of the driving parts for the adding mechanism and printing mechanism.

The amount keys 10 co-operate in a well-known manner with locking rockers 12, illustrated as broken away in Figure 1. Upon depression of an amount key, the rockers 12 are raised and held in this position by locking supports 13 rocked backward by spring action, until the latter return to initial position, whereby the rockers 12 and the depressed amount keys also return to initial position. The locking supports 13 are moved back by a releasing shaft 14, the pins 15 of which engage lugs 16 of the supports 13 and take the latter with them. The rotation of the releasing shaft 14 is caused by a cam disk 17 at the end of the operation, said cam disk acting through a roller 18 on an extension 19 of a thrust rod 21. The latter has an angular slot 22 into which projects a pin 23 of an arm 24 fixed on the releasing shaft 14. As long as this pin 23 engages the horizontal section of the angle slot 22, the arm 24 and the releasing shaft 14 take part in the motion of the thrust rod 21, however, when the latter is swung to the left, so that the pin 23 engages the upper end of the vertical section of slot 22, the releasing shaft 14 is not acted upon by rod 21 and no release of the amount keys takes place at the end of the operation. The rod 21 further has another slot 25 engaged by a pin 26 of a double-armed lever 27 the other arm of which has a pin 28 engaging a locking slide 29. The locking slide co-operates with the pins 31, 32, 33 of three special keys E, O, D, serving to start the cash operations. By depressing normal key E a normal operation takes place issuing a simple voucher without an action upon the subsequent operations. By depressing repeat key O an operation is caused in which

- an original voucher is issued, and the machine is set for a repeat operation to be initiated by depressing duplicate key D which causes a duplicate voucher to be issued. An inclined face 34 is provided on slide 29 in the path of the key pin 32 and an oppositely directed inclined face 35 in the path of the key pin 33. Two notches 36, 37 are further provided on the rear narrow face of slide 29, with which notches co-operates a spring-actuated locking pawl 38, the object of which is to hold the slide 29 resiliently in its extreme positions. By depressing key D the slide 29 is shifted by the inclined face 35 into its lower extreme position, Figure 1, whilst by depressing key O it is shifted into the upper one by the inclined face 34. In this latter position of slide 29 a locking face 39 arranged on it lies below pin 31 of key E, and further the thrust rod 21 is swung toward the left through the intermediary of lever 27, so that by depressing key O key E is locked and the release of the amount keys is prevented.
- 25 A locking segment 42 is pivotally mounted at 41 on slide 29 in the plane of the key pins 32, 33, which segment is resiliently held in a middle position by a spring 43 attached to a downwardly extending arm 44 of segment 42. In this middle position of segment 42 a locking face 45 arranged concentrically to pivot pin 41, and two inclined faces 46, 47 limiting face 45 are located symmetrical- 30 ly to the inclined faces 34, 35 of slide 29. When the latter is in its lower extreme position, Figure 1, the lower portion of the locking face 45 is below pin 33 of key D. Due to face 45 being arranged concentrically to pivot pin 41, the key D is hereby locked, as 35 the force exerted upon segment 42 by the pressure exerted on key D is normal to the point of contact and passes through the fulcrum of segment 42, so that the latter is unable to give way laterally. In the same manner key O is locked by segment 42, when slide 29 assumes its upper extreme position.
- 40 The hereinbefore described arrangement serves to lock the keys O and D, when they return to position of rest, so that in every case only one of them and each of them only once can be depressed. For, when slide 29 is in its extreme lower position illustrated in Figure 1, in which the key D is locked, and when key O is now depressed, slide 29 is shifted by the inclined face 34 into the extreme upper position together with segment 42, in which position key D is released by the locking face 45. The pin 32 of key O has at the same time arrived behind the inclined face 46 of segment 42. Upon key O now being returned into position of rest at the end of the operation concerned, pin 32, by engaging the inclined face 46, presses segment 42 downward against the action of spring 43, until pin 32 assumes its position of rest,

when segment 42 snaps back and the locking face 45 engages below pin 32 and thus locks key O. In the same manner key D is locked upon returning from depressed position to position of rest.

70 The locking of the special keys E, O, D in the depressed position is effected like that of the amount keys by a locking rocker 48, but no locking support 13 mounted on shaft 14 is provided for this locking rocker of the special key board. On the contrary, the locking rocker 48 has a lug 49 that co-operates with the front arm 51 of the cash releasing lever 52. The latter co-operates through a roller 53 of its rear arm 54 with an inclined face 57 arranged on an arm 55 rigid on the main actuating shaft 56. In the position of rest of the machine the hook-shaped front end 58 of arm 51 abuts on the upper face of lug 49 under the action of a spring 60, the rear arm 54 being swung downwards and locking the driving mechanism. When a special key is depressed, e. g. key E, as shown in Figure 1, the locking rocker 48 is rocked upwards, so that the lug 49 releases the hook 58 and the cash operation is thus released in known manner. The hook 58 arrives at the same time below the lug 49 and maintains the rocker 48 in the raised position and the depressed special key in the depressed position. At the end of the operation of the machine the releasing lever 52 is swung back through the intermediary of the inclined face 57 and roller 53 into locking position, by which motion it releases the rocker 48 and the depressed special key, which both return to position of rest under the action of their springs.

90 In order to prevent the amount introduced by the amount keys from being transmitted to the adding mechanism 20 during a duplicate issuing operation, the disengagement of this mechanism is prepared by the depression of key D. To this end the key pin 33, Figure 2, co-operates with a lever 59, 61, which, through the intermediary of a roller 61' and an intermediate lever 62, 63, acts upon a double lever 65, 66 fast on a shaft 64. The double lever 65, 66 is adapted to co-operate by means of a roller 67 with a cam disk 68 and assumes the position shown in Figure 2, when key D has not been depressed, in which position the roller 67 is out of the path of the rise 69 of the disk 68. Upon depressing key D, roller 67 is rocked into the path of rise 69 through the intermediary of levers 59, 61, 62, 63 and 65, 66, so that lever 65, 66 may have imparted to it a farther rotation by the disk 68 in the subsequent cash operation. A second two-armed lever 70 rigidly mounted on shaft 64 is brought, upon depression of key D, into a position in which a pin 109 thereon is in contact with a rocking frame 105 rotatably mounted upon a stationary shaft 106 (Fig. 95 100 110 115 120 125 130

4). On the upper end of the rocking frame 105 a coupling pinion 104 is rotatably mounted upon a pin 107. The coupling pinion stands in mesh with two toothed wheels 102, 103 of the same size. The toothed wheel 102 is connected by a hollow shaft 111 with a type segment 108 (Figs. 5 and 6), and receives its adjustment from a setting segment 101 (Fig. 4) and a setting device of the type 10 shown in Patent No. 1,508,953. The toothed wheel 103 is mounted to rotate freely on the same hollow shaft and is in constant engagement with a toothed wheel 110 rigidly fixed to a number wheel 20, so that the adjustment 15 of the setting segment 101 is carried over to the adding mechanism 20, when the coupling pinion 104 is thrown in. On the other hand the transmission is prevented when, by depression of key D the roller 67 is brought 20 into the path of the cam disk 68 and the pin 109 in engagement with the rocking frame 105, for in the following operation of the machine the additional turning of the shaft 64 by roller 67 and lever 66 swings out the pin 25 109 and the rocking frame 105 and thereby throws out the coupling pinion 104, so that only the toothed wheel 102 is turned and the type segment 108 adjusted while the adding mechanism 20 remains stationary. The second arm of lever 70 is under the influence of 30 a spring, which causes the restoration of the two-armed levers 66, 65; 63, 62; 61, 59 when the key D is released.

By the depression of key D the consecutive number feeding mechanism is thrown out of operation at the same time. This mechanism is actuated by a cam 71, Figure 2, that acts upon a roller 72 of a lever 75 mounted on a journal 74 and urged in clockwise direction 40 by a spring 73. Lever 75 is further hingedly connected to a rod 76 by a pin 78 engaging an open slot 77 of the rod 76. The rod 76 is coupled by a connecting pin 98 to the rocker 79 of the consecutive number mechanism (not shown). The connecting pin 98 carries in known manner a shifting pawl 99 provided with several arms of different lengths and under the influence of a spring, which pawl operates upon the transmission 45 wheels 100 and controls the advancing of the consecutive number in known manner (Figs. 5 and 6). A platen 112 cooperating with both the consecutive number type wheels connected with transmission wheels 100, and with the amount type segments 108 is operated in known manner by the driving mechanism of the machine to take an impression. In the revolution of cam 71 occurring during each cash operation, the rocker 79 is rocked to and fro once, this motion each time causing the mechanism to be fed one unit. A link 81 is connected to rod 76, which link is in connection with the lever 59, 61 through an angle lever 82 and another link 83. Upon the key 50 D being depressed, due to this connection the

rod 76 is rocked upwards, whereby the connection between the rocker 79 and the lever 75 is interrupted. As long as key D is depressed, a feeding of the consecutive number thus does not take place.

The described arrangement, that is intended for the issue of one duplicate, operates in the following manner:

In the normal position of the machine the locking slide 29 assumes its lower extreme position, in which the keys E and O are released and key D is locked by segment 42. Now, when key E is depressed, after the amount keys have been set, a cash operation takes place, in which the amount set is transmitted to the adding mechanism, the consecutive number is fed and a voucher is issued. At the end of the cash operation the depressed amount keys are released by rod 21 and the key E by lever 52, so that all the controlling members of the machine assume the same position as before the beginning of the operation. Upon depressing key E a normal cash operation takes place which has no influence upon the subsequent ones.

When, however, the key O is depressed, firstly the locking slide 29 is shifted into its upper extreme position and secured therein by pawl 38. This shift results in the rod 21 being rocked forward. At the end of the cash operation, during which the original voucher is issued, the amount is transmitted to the adding mechanism, and the consecutive number mechanism is fed one unit, the key O is released, but the amount keys remain in their set position, as pin 23 is located in the vertical portion of the angular slot 22. Furthermore, upon slide 29 being shifted upward, the locking face 39 arrives under the key pin 31, while segment 42 passes from the range of key D over into that of key O, so that, after key O has returned into position of rest, the keys E and O are locked, but key D is released. As can be seen, the execution of a duplicate issuing operation is thus enforced as a consequence of an operation that issues an original voucher, operation of key O causing the issuance of an original voucher and at the same time presetting the machine for the operation of key D.

Upon depressing key D the adding mechanism and the consecutive number feeding mechanism are thrown out of gear by the lever 59, 61, so that the amount still set in the amount keys from the preceding operation is not transmitted to the adding mechanism, but is printed on the duplicate. The latter receives also the same consecutive number as the original. The depression of key D further causes the locking slide 29 to return into its lower position and the horizontal portion of the angle slot 22 to arrive over pin 23, so that the amount keys are released at the end of the cash operation. When the key D is released by lever 52, lever 59, 61

returns to position of rest, so that the drive of the consecutive number feeding mechanism and the adding mechanism are thrown in again. The locking segment 42 arrives below pin 33 of key D, which segment had released key O when slide 29 moved downward. As pin 31 is also released by the locking face 39, the normal state of the machine is re-established, that is, the keys E and O are released and key D is locked.

In a manner not shown the keys E, O, D effect the setting of a symbol type wheel, by means of which a symbol corresponding to the depressed key is printed on the voucher to be issued, to denote it as normal voucher, original voucher or duplicate. A further control of the recording operation is obtained by printing all impressions also on the control strip.

In order to make the described mechanism applicable to the issue of more than one duplicate, it is modified as illustrated in Figure 3. In this modification the locking slide is not moved back into its lower extreme position upon the first depression of key D, but only after a determined adjustable number of strokes of key D. The locking slide, which has the same configuration as in the first-described embodiment, carries the locking segment 42, Figure 1, and is resiliently held in its two extreme positions by the pawl 38. For the sake of clearness, segment 42 has been partly cut away and pawl 38 entirely omitted in Figure 3. The inclined face 35, however, is cut away, so that the key pin 33 is unable to act immediately upon slide 29.

The key pin 33 of key D carries a spring-influenced pawl 84 co-operating with a series of ratchet teeth 85 of a plate 87 pivoted on the key frame by a pin 86. An upward extension 89 of plate 87 abuts on a stop 91 under the action of a spring 88. When plate 87 is turned in counter-clockwise direction, the extension 89 comes to abut on a stop 92 of the locking slide and carries the latter with it into the lower extreme position. Another stop 93 of slide 29 co-operates with a pawl 94 pivoted on the key frame and adapted to engage the series of ratchet teeth 85 under the action of a spring 95. Upon the slide 29 moving however from the upper to the lower extreme position, the pawl 94 is lifted from the teeth 85 by the stop 93. The stop 91 is carried by an adjusting member 96 which is rockingly mounted on the pin 86 and an adjusting arm 97 of which projects beyond the cabinet of the machine. By suitable means (not shown) the arm 97 may be fixed in different angular positions denoted by 1, 2, 3, whereby the extension 89 of plate 87 is made to approach more or less, the stop 92 of the locking slide 29 and the number of the duplicates to be issued is regulated.

In the normal position of the machine the

described mechanism assumes the position illustrated in Figure 3. It may be supposed, that the arm 97 has been set to position 2 (issue of two duplicates). Upon depressing key O, slide 29 is shifted into the upper extreme position by means of the inclined face 34, whereby the pawl 94 is released by stop 93 and falls into the series of teeth 85. At the end of the machine operation initiated by key O the amount keys remain in their set position, key O is locked by segment 42, Figure 1, and key D is released. Upon now depressing key D, plate 87 is turned one unit by pawl 84 and is held in the new position by pawl 94. At the end of the cash operation, in which the adding mechanism and the drive of the consecutive number mechanism remain out of gear due to the action of key D on lever 59, 61, Figure 2, key D is released. The keys O and E remain locked as before and also the amount keys are retained in the set position, as slide 29 is still in the upper extreme position. To start the next operation only key D can be depressed. By this depression plate 87 is turned one unit further by pawl 84, the extension 89 striking the stop 92 and shifting slide 29 back into the lower end position, so that the release of the amount keys may take place at the end of the cash operation, segment 42 arrives from the range of key O into that of key D, key E is released and pawl 94 is lifted by stop 93 from the teeth 85. When key D is moved back into position of rest at the end of this last duplicate issuing operation, plate 87, which had been locked by pawl 84 after pawl 94 has been lifted, also returns, under the action of its spring 88, until its extension 89 abuts on the adjustable stop 91. In position of rest key D is locked by segment 42, so that the normal position of the machine is re-established. If arm 97 had been set to position 3, in which the extension 89 moves only in the third stroke of key D, three duplicate issuing operations would have been required to return the machine to normal state. When arm 97 assumes position 1, slide 29 is lowered already in the first stroke of key D, so that only one duplicate is issued.

Instead of the maximum issue of three duplicates any other desired number of duplicate issues may of course be provided for by correspondingly designing the series of ratchet teeth 85.

What we claim and desire to secure by Letters Patent, is:

1. In a machine of the class described three special keys, a locking device normally freeing the first two of said keys and locking the third one, operative connections between said locking device and the second key whereby upon depressing the second key the first key is locked and the third key is freed, and operative connections between the third key

and said locking device whereby upon depressing the third key the first and second keys are freed.

2. In a machine of the class described three special keys, a locking device adapted to lock one of said keys, means whereby said locking device is made operative by the second key and to be made inoperative by the third key, and another locking device between said second and third key adapted to prevent either the second or the third key from being depressed more than a determined number of times in succession.

3. In a machine of the class described two keys, a locking device adapted to prevent the first key from being depressed more than once in succession, a locking means for normally locking the second key and adapted to be made inoperative by depressing the first key, and a returning device for relocking the second key and freeing the first key after an adjustable number of actuations of the second key.

4. In a machine of the class described a key, a locking slide adapted to co-operate therewith and to be moved by depressing the key, a locking means movably mounted on said locking slide and adapted to be put into operative position when said locking slide is moved upon depressing the key so as to lock the key as soon as it is returned to its position of rest.

5. In a machine of the class described a totalizer, a consecutive number device, means for adjusting said totalizer into operative position, comprising a manipulative means, a driving member, a lever connection connected with said totalizer and adapted to be put into preparatory position in which it can be engaged by said driving member upon operation of said manipulative means and to adjust the totalizer into inoperative condition when driven by said driving member, an actuating device adapted to actuate said consecutive number device at each operation of the machine, disengageable connections in said actuating device, and means controlled by said lever connection for disengaging said disengageable connections and rendering said actuating device inoperative as long as said totalizer is in inoperative condition.

6. The combination with a machine as specified in claim 17 of an actuating device adapted to actuate a consecutive number device at each operation of the machine, disengageable means thereon and connections between said disengageable means and said duplicate key adapted to make inoperative said actuating device upon operation of said duplicate key.

7. In a machine of the class described three keys, a locking slide having a slot and a locking face adapted to co-operate with the first of said keys, an inclined face adapted to co-operate with the second key adapted to move

the locking slide to one of its end-positions, where said locking face locks the first key, a step by step mechanism actuated by the third key and adapted to move said locking slide to its other end-position upon a definite number of depressions of the third key where the first key is freed by said slot.

8. In a machine of the class described a slide having two positions, a step by step mechanism comprising a ratchet segment, a spring attached thereto, a restraining pawl for maintaining the ratchet segment in its position against the action of the spring, a projection on the slide adapted to co-operate with said ratchet segment and to enable the slide to be moved to its second position upon a definite number of step actuations of said ratchet segment, a lug on said slide adapted to co-operate with said restraining pawl and to throw-out said restraining pawl when the slide reaches its second position whereby the ratchet segment becomes free to return under the action of said spring.

9. The combination with a machine as specified in claim 8, of a stop member adapted to co-operate with said ratchet segment, and to stop the return movement of the latter, manipulative means therefor adapted to adjust the stop member in different positions, so as to regulate the number of step actuations, after which the ratchet segment moves the slide into its second position.

10. In a machine of the class described, amount setting means, a totalizer, means establishing an operative relation between said amount setting means and said totalizer, releasing means for said amount setting means adapted to release them at the end of an operation of the machine, manipulative means for issuing an original voucher manipulative means for issuing duplicate vouchers, means actuated by said first manipulative means, when operated for issuing an original voucher, for making said releasing means inoperative and preparing the making inoperative of said establishing means during the subsequent operation of said second manipulative means.

11. In a machine of the class described, means for setting the machine for entering amounts, retaining means for said setting means, releasing means for said retaining means operated by the driving mechanism of the machine, a common manipulative means for setting the machine to print an original voucher and for rendering said releasing means inoperative, and a common manipulative means for setting the machine to print a duplicate voucher and for rendering said releasing means operative again.

12. In a machine of the class described, means for setting the machine for entering amounts, retaining means for said setting means, releasing means for said retaining means operated by the driving mechanism of

the machine, the manipulative means for setting the machine to print an original voucher, connections between said manipulative means and said releasing means adapted to render the latter inoperative when said manipulative means is operated, and manipulative means for setting the machine to print a duplicate voucher, said last mentioned manipulative means being adapted to operate upon said connections to return said releasing means to operative condition.

13. In a machine of the class described, means for setting the machine for entering amounts, retaining means for said setting means, releasing means for said retaining means operated by the driving mechanism of the machine, a common manipulative means for setting the machine to print an original voucher and for rendering said releasing means inoperative, a common manipulative means for setting the machine to print a duplicate voucher and for rendering said releasing means operative again, and a third manipulative means for setting the machine for printing a single voucher.

14. In a machine of the class described, three keys for setting the machine for three different kinds of operation, a locking slide having a slot and a locking face cooperating with one of said keys, cam means cooperating with a second of said keys, upon depression thereof, for positively moving said locking slide into one of its end positions, in which said locking face locks said first mentioned key, and cam means cooperating with the third of said keys, upon depression thereof, for positively moving said locking slide into its other end position, in which said slot frees said first mentioned key.

15. In a machine of the class described, two keys, pins on said keys, a locking slide, means cooperating with said key pins to move the locking slide from one end position to another and vice versa, a locking member mounted on said locking slide, means for yieldingly holding said locking member in a middle position, said locking member being adapted to lock one or the other of said key pins, according to whether said slide is in one end position or the other, two inclined faces on said locking member covering the pin of the depressed key and yielding to said pin upon the return of said key, so as to enable said locking member to snap under said pin, when the key reaches its position of rest, after a determined number of depressions.

16. In a machine of the class described, two keys, pins thereon, a locking slide having means cooperating with said key pins to move said locking slide from one end position to another and vice versa, a locking member pivoted to said locking slide, means yieldably holding said locking member in a certain relation to said slide, said locking member having a locking face cooperating

with said key pins, said locking face being concentric with respect to the pivot of said locking member, said pins being arrested, upon striking said locking face, without moving said locking member.

17. In a machine of the class described, amount setting means, a totalizer, differential means controlled by said amount setting means, releasing means for said amount setting means adapted to be operated by the driving mechanism of the machine, a repeat key and a duplicate key each adapted to release the driving mechanism of the machine, means whereby said totalizer is coupled to said differential members during an operation of the machine released by said repeat key, means whereby said releasing means is rendered inoperative by depression of said repeat key, means whereby said coupling means is rendered inoperative by depression of said repeat key and a duplicate key, and means whereby said releasing means is restored to operative condition upon depression of said duplicate key.

18. The combination with a machine as specified in claim 17, of locking means between said two keys compelling the operation of the machine following an operation initiated by said repeat key to be initiated by said duplicate key.

19. In a machine of the class described, amount setting means, a totalizer, differential means controlled by said amount setting means, means for coupling said totalizer to said differential means, manipulative means adapted to release an operation of the machine in which said coupling means is operative, and means whereby the machine is set by said manipulative means for a subsequent operation in which said coupling means is inoperative.

20. The combination with a machine as specified in claim 17, of a normal key adapted to release a normal operation of the machine in which said coupling and releasing means are both operative, a locking device adapted to lock said repeat and normal keys when the former is depressed, said locking means being adapted to release said repeat and normal keys when said duplicate key is depressed.

21. In a machine of the class described, amount setting means, a totalizer, differential means controlled by said amount setting means, releasing means for said amount setting means adapted to be operated by the driving mechanism of the machine, a repeat key and a duplicate key each adapted to release the driving mechanism of the machine, means whereby said totalizer is coupled to said differential members during an operation of the machine released by said repeat key, means whereby said releasing means is rendered inoperative by depression of said repeat key, means whereby said coupling means is rendered inoperative by depression of said dupli-

cate key, and adjustable means whereby said releasing means is restored to operative condition at the last of a predetermined number of depressions of said duplicate key.

5 22. In a machine of the class described, amount setting members, differential mechanism controlled thereby, a printing mechanism connected with said differential mechanism, a totalizer, means for coupling said totalizer to said differential mechanism, manipulative means adapted to release an original voucher printing operation of the machine in which said coupling means is operated, manipulative means adapted to release a duplicate voucher printing operation, and mechanism controlled by said last-named manipulative means adapted to render said coupling means inoperative.

23. The combination with a machine as specified in claim 22, of a blocking device adapted to enforce an alternate operation of said manipulative means.

24. The combination with a machine as specified in claim 22, of releasing means for said amount setting members adapted to be operated by the driving mechanism of the machine, means controlled by said first-mentioned manipulative means for rendering said releasing means inoperative, and means controlled by said second-mentioned manipulative means for restoring said releasing means to operative condition.

The foregoing specification signed at Cologne, Germany, this 16th day of July, 1928.

35 KARL AUGUST LEHMANN.
ALEXANDER VARREN.
